UNITED STATES PATENT OFFICE.

GEORGE S. HASTINGS, OF PHILADELPHIA, PENNSYLVANIA.

DESIGN FOR A BODY-BOLSTER FOR RAILWAY-CARS.

SPECIFICATION forming part of Design No. 32,821, dated June 12, 1900.

Application filed January 4, 1900. Serial No. 397. Term of patent 14 years.

To all whom it may concern:

Be it known that I, GEORGE S. HASTINGS, a citizen of the United States, residing at Philadelphia, in the county of Philadelphia and State of Pennsylvania, have invented and produced a new and original Design for a Body-Bolster for Railway-Cars, of which the following is a specification.

The essential feature of my invention resides in the shape or configuration of the body-bolster hereinafter described.

In the drawings forming part of this specification, Figure 1 is a perspective elevation; Fig. 2, a plan view; Fig. 3, a section on the line 3 3, Fig. 2, looking in the direction of the arrow; Fig. 4, a like view on the line 4 4, Fig. 2; and Fig. 5, a like view on the line 5 5, Fig. 2. 1 indicates the upper horizontal flange, 2 the lower horizontal flange, and 3 a centrally-located vertically-connecting web. Considered as a whole, thus including both flanges 1 2, the bolster has elevated ends and middle portions 4 4^a 5 5^a 6 and depressed intermedi-

ate portions 7 8. The depressed portions of the flange 1 are formed with lateral grooves 9, to which the web of the flange 1 converges from the elevated portions 4 5 6, as at 10 11. At the ends the flange 1 is dropped, as at 12^a, to form a ledge 12, between which and the lower flange 2 is a longitudinal web 13. At 13^a the groove 9 the flange 1 is widened laterally, as shown at 13^b, and from the web 12^a and flange 2 extend lateral ears 12^b. The flange 2 has lateral ears 15, and between the flanges 1 2 the web 3 is provided with a vertical rib 16.

Having described my invention, I claim—

The design for a body-bolster, substantially as herein shown and described.

Signed at the city of Philadelphia, county 40 of Philadelphia, and State of Pennsylvania, this 4th day of November, 1899.

GEORGE S. HASTINGS.
